UNITED STATES PATENT OFFICE.

THOMAS R. BRUMFIELD, OF DANVILLE, VIRGINIA, ASSIGNOR OF ONE-HALF TO POSIE L. HINES, OF DANVILLE, VIRGINIA.

COMBINED NUT AND BOLT LOCK.

Application filed October 16, 1924. Serial No. 744,085.

To all whom it may concern:

Be it known that I, THOMAS R. BRUMFIELD, a citizen of the United States, residing at Danville, in the county of Pittsylvania and State of Virginia, have invented certain new and useful Improvements in Combined Nut and Bolt Locks, of which the following is a specification.

The present invention appertains to a combined nut and bolt lock and has for its prime object to provide a device of this nature which is capable of easy manipulation for assembling the various parts and which will be most efficient in preventing said parts from becoming accidentally disassembled or unlocked.

Another very important object of the invention is to provide a device of this nature possessing a very simple and effective construction, one which is thoroughly reliable, extremely economical to manufacture, strong, durable, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is an end elevation of an assemblage embodying the features of this invention,

Figure 2 is a transverse section therethrough taken substantially on the line 2—2 of Figure 1,

Figure 3 is a somewhat similar section to that shown in Figure 2 but at right angles thereto,

Figure 4 is a plan view of the nut,

Figure 5 is a section therethrough taken on the line 5—5 of Figure 4,

Figure 6 is a perspective view of the lock washer,

Figure 7 is a view showing in detail the construction of the ends of prongs used in conjunction with the device, and

Figure 8 is a detail perspective of the lock sleeve.

Referring to the drawing in detail it will be seen that numerals 1 and 2 represent two members which it is desired to hold together by means of a bolt. The bolt is shown at B

and embodies the ordinary conventional construction. The nut N is provided with the usual interior threaded portion besides having a pair of diametrically opposed grooves 3 extending across the threaded interior. A lock sleeve S is formed with an elongated cylindrical body 4 having prongs 5 extending from one end and at its other end provided with notches 6. The prongs 5 are provided with beveled ends 7 and are diametrically opposed to each other. The notches 6 are also diametrically opposed to each other one alining with each prong 5. This locking sleeve is assembled with the nut by inserting the prongs 5 into the grooves 3, the beveled ends 7 allowing this to be easily done. The locking sleeve is then projected through openings provided in the members 1 and 2.

A lock washer W which is shown to advantage in Figure 6 is formed with a plurality of bendable ears 9 extending from its outer periphery and a pair of prongs 10 with beveled ends 11 extending from the edge of the opening 12 which is centrally located. These prongs 10 extend at right angles from the body of the washer W and the beveled ends 11 are similar in construction to the beveled ends 7 of prongs 5. This washer W is placed over the bolt B adjacent the head thereof and the prongs 10 extend into the notches 6 of the locking sleeve S when the bolt is inserted in this sleeve. As the bolt is inserted in the sleeve and the threaded portion thereof comes into contact with the threads of the nut, the bolt is turned so as to threadedly engage the nut until the members 1 and 2 are brought tightly together as may be desired. One of the ears 9 is then bent up alongside of the head of the bolt B as is indicated to advantage in Figures 1 and 2. It will thus be seen that both bolt and nut are locked in engagement with the lock sleeve S and it will be impossible to remove the nut accidentally. If at any time

it is desired to disassemble the bolt and nut, the ear 9 is bent out of engagement with the head of the bolt B and said bolt is then free to be unscrewed from engagement with the nut. The sleeve S not only functions as described above but also acts as an efficient bushing for the bolt and the cost of the entire assemblage is not much more than the ordinary bolt, nut, and bushing.

It will be apparent from the above that I have devised a novel construction of this nature which may be easily and quickly assembled and disassembled, which will be 5 cheaply manufactured and will be durable and effective under all conditions and which is not liable to get out of order.

The embodiment of the invention which I have described in detail possesses all the 10 features of advantage enumerated as desirable in the statement of the invention and the above description and while I have in the present instance shown and described a preferred embodiment of the invention which 15 will give in practice satisfactory and reliable results, it is to be understood that the same is susceptible of numerous changes in the details of construction and in the combination and arrangement of parts without de- 20 parting from the spirit or scope of the invention as hereinafter claimed or sacrificing any of its advantages.

Having thus described my invention, what I claim as new is:

- 25 1. A combination with a bolt and nut, a bushing received on the bolt, means between one end of the bushing and nut for holding the latter against rotation, a bendable washer associated with the bolt adjacent the head 30 thereof and adapted to be bent against the latter to hold the bolt against rotation, and elements carried by the washer having interlocking engagement with the bushing to lock the latter and the washer together.
- 35 2. A device of the class described including in combination a lock sleeve provided with notches at one end, a bolt insertable through the sleeve, a washer on the bolt having a bendable ear to engage the head of the 40 bolt and provided with prongs adapted to fit in the notches of the sleeve, a nut threaded

on the bolt and means for locking the nut to the sleeve.

3. A device of the class described including in combination a lock sleeve forming a 45 bushing and provided at one end with a notch and at its other end with a prong, a bolt in the sleeve, a washer on the bolt embodying means for locking the same to the bolt and provided with a prong insertable in 50 the notch, a nut threaded on the bolt and provided with an interior groove for receiving the prong extending from the sleeve.

4. A device of the class described including in combination a lock sleeve forming a 55 bushing and provided at one end with a notch and at its other end with a prong, a bolt in the sleeve, a washer on the bolt embodying means for locking the same to the bolt and provided with a prong insertable in 60 the notch, a nut threaded on the bolt and provided with an interior groove for receiving the prong extending from the sleeve, said prongs being provided with beveled 65 ends.

5. A device of the class described including in combination a lock sleeve provided at one end with a pair of notches and at its other end with a pair of prongs having beveled ends, a bolt extending into the sleeve, a 70 washer on the bolt provided with bendable ears on its outer edge for engagement with the head of the bolt and at its inner edge with a pair of prongs extending at right angles to the washer and insertable in the 75 notches of the sleeve, said prongs being provided with beveled ends, and a nut threaded on the bolt and provided with a pair of grooves for receiving the prongs extending 80 from the sleeve.

In testimony whereof I affix my signature.
THOMAS R. BRUMFIELD.
